INVENTOR

Frank Moore,
By his attorney
Garrison, Garrison,
Inc. at atty.

UNITED STATES PATENT OFFICE.

FRANK MOORE, OF PITTSBURGH, PENNSYLVANIA, ASSIGNOR TO PITTSBURGH MALLEABLE IRON COMPANY, OF PITTSBURGH, PENNSYLVANIA, A CORPORATION OF PENNSYLVANIA.

WRENCH.

Application filed April 22, 1924. Serial No. 708,179.

The present invention relates particularly to wrenches, and more particularly to wrenches adapted to be utilized for the gripping and turning of circular objects.

5 It has heretofore been proposed to construct wrenches of the general character to which this invention relates embodying a fixed gripping jaw and a rotatable gripping jaw tending to increase its bite in accordance
10 with the pressure exerted to effect turning. One of the objects of the present invention is to improve a wrench of this type by providing means co-operating with the rotatable gripping element in such manner as to
15 limit the possible depth of penetration of the gripping teeth provided thereon and also to increase the area of engagement between the wrench and the article being gripped to thereby distribute the load over a greater
20 surface.

The invention also has for one of its objects the construction of a wrench which may be easily produced largely from sheet metal, thereby facilitating the manufacture thereof and decreasing the cost of production.

In the accompanying drawings, there is shown, for purposes of illustration only, one form of wrench constructed in accordance with the present invention, it being understood that the drawings do not define the limits of my invention, it being contemplated that changes in the construction and operation disclosed therein may be made without departing from the spirit of the invention or scope of my broader claims.

In the drawings:—

Figure 1 is a side elevation of a wrench embodying the present invention;

40. Figure 2 is a view, similar to Figure 1, illustrating a portion of the wrench in section;

Figure 3 is a transverse sectional view on the line III—III of Figure 2, looking in the direction of the arrows;

Figure 4 is a transverse sectional view on the line IV—IV of Figure 2, looking in the direction of the arrows;

59. Figure 5 is a detail view of a portion of the shank;

Figure 6 is a detail view of the fixed gripping jaw;

Figure 7 is a perspective view of the follower for compressing the spring; and

Figure 8 is a transverse sectional view on the line VIII—VIII of Figure 2.

In accordance with the present invention, there may be provided a shank 2 constructed preferably of sheet metal and shaped to provide a handle portion 3 of substantially oval section, as illustrated clearly in Figure 8, and a jaw-receiving portion 4 of substantially U-shaped cross-section, as clearly illustrated in Figure 4. The shank may conveniently be formed from a single piece of sheet metal and shaped to provide a rack bar 5 along each edge of the jaw-receiving portion. 60 65

Mounted between the sides of the jaw-receiving portion is a fixed jaw 6 which may be suitably secured in position as by welding or brazing, the jaw preferably being shaped in such manner as to effectively co-operate with an article A having a curved surface, as illustrated in Figure 1. A pin or rivet 7 may be used to initially center the jaw. 70 75

Mounted to slide longitudinally along the portion 4 of the shank 2 is a U-shaped sleeve 8 which is preferably so shaped as to substantially conform to the contour of the portion 4 of the shank 2 with which it cooperates. The sides 9 of the sleeve are extended to form guard portions adapted to receive therebetween a rotatable gripping element 10 having its periphery provided with a series of gripping teeth 11 which extend a slight distance beyond the guards 9 adjacent the jaw 6. The gripping element 10 is rotatable about its longitudinal axis.

10 is rotatably secured in position by a suitable pin or bolt 12 and is provided preferably on each side thereof with a pinion 13 which may be formed either integrally with the movable gripping element or secured thereto in any desired manner to provide a substantially unitary construction. The gripping element 10 is preferably of such width that it may freely rotate between the sides of the jaw-receiving portion, as clearly illustrated in Figures 2 and 3, and the pinions 13 are adapted to engage the respective rack bars 5 on the faces of the portion 4 of the shank 2. By reason of this construction, it will be apparent that, by merely gripping the sleeve 8 and moving the same longitudi- 90 95 100

nally of the shank, the distance between the gripping elements may be varied and, at the same time, the element 10 will be rotated to bring different portions of its periphery 5 into operative gripping position for different sized articles to be gripped. In this manner, wear on the rotatable gripping element is distributed throughout its entire periphery and the length of life of the 10 wrench is correspondingly increased.

For normally urging the sleeve 8 and its associated parts into position to engage an article between the gripping elements, there is provided a spring 14 encircling a guide 15 rod 15 carried at one end by a pin 16 extending through the handle portion of the shank, and at its opposite end engaging a projection 17 on a follower 18 secured to the sleeve. This follower is so shaped that it 20 may embrace the sides of the sleeve 8, and as clearly illustrated in Figure 7, the projection 17 may be formed with an opening 19 for receiving the rod 15. The mounting of the rod 15 is such that it may move about 25 the pin 16, thereby accommodating itself to any slight irregularities in construction and permit movement of the sleeve without any binding action.

In operation, the elements will be separated 30 the required distance to receive an article to be gripped therebetween by moving the sleeve 8 against the action of the spring 14. Immediately upon releasing the sleeve, the spring will urge the element 10 toward 35 the fixed jaw to effect engagement with the article on substantially diametrically opposite sides thereof. As the wrench is operated in the direction indicated by the arrow B in Figure 1, to effect rotation of the article 40 in a clockwise direction, the gripping element 10 will tend to rotate in a clockwise direction as viewed in this figure, thereby increasing the biting action exerted on the article by the wrench.

With some articles such as pipe having a thin wall, the action of the teeth on the gripping element 10 may be such that, if uncontrolled, they will objectionably penetrate or disfigure the surface of the article. This 45 objectionable tendency of the wrench is successfully overcome in the present invention by the provision of the guards 9, which come into engagement with the article being gripped after the teeth on the rotatable gripping element have penetrated the surface 50 of the article a distance corresponding to their projection beyond the periphery of the guards, as clearly shown in Figures 1 and 2. This engagement of the guards on opposite sides of the gripping element 10 prevents further penetration of the teeth and, 55 at the same time, increases the effective gripping area of the movable gripping element, from the outer face of one guard 9 to the outer face of the other guard (see Fig. 3),

thereby distributing the load over a greater portion of the article. This operation has been found to be highly advantageous.

Preferably, the guard portions 9 are so shaped that they project beyond the major 70 portion of the periphery of the element 10, except at the point of contact adjacent the jaw 6, thereby serving to shield and protect the teeth of the same. This may be accomplished by mounting the movable gripping element eccentrically with respect to the guards, or by cutting away a portion of the guards to permit the desired projection of the comparatively small portion of the movable gripping element at the point 75 of contact.

The advantages of the present invention arise from the provision of a wrench having a movable gripping element and a fixed gripping element with means co-operating with 80 one of the gripping elements to modify the action thereof.

Further advantages of the present invention arise from the provision of a wrench constructed largely of sheet metal, whereby 90 the manufacture thereof is facilitated.

I claim:—

1. In a wrench, a shank having a rack bar, a sleeve movable along said shank, a pinion journaled in said sleeve and meshing with said rack bar, a gripping element movable with said pinion, and a non-rotatable guard co-operating with said gripping element, substantially as described. 95

2. In a wrench, a shank having a rack bar, a sleeve movable along said shank, a pinion journaled in said sleeve and meshing with said rack bar, and a gripping element carried by said pinion, said sleeve co-operating with said gripping element to limit the extent of penetration of said gripping element into the article being gripped, and provide non-rotatable engaging surfaces, 100 substantially as described. 105

3. In a wrench, a shank having a rack bar, a sleeve movable along said shank, a pinion journaled in said sleeve and meshing with said rack bar, and a gripping element carried by said pinion, said sleeve extending on opposite sides of the gripping element and adapted to engage the article being gripped under predetermined conditions of operation of the wrench, on opposite sides 110 of the gripping element, substantially as described. 115

4. In a wrench, a shank comprising a handle portion and a jaw receiving portion, said jaw receiving portion being of substantially U-shape in cross-section and adapted to receive a gripping jaw between the sides thereof, a sleeve embracing said jaw receiving portion, a rotatable gripping element carried by said sleeve, and non-rotatable means co-operating with said rotatable gripping element and movable therewith for in- 120 125 130

creasing the effective contact area with the article being gripped under predetermined conditions of operation, substantially as described.

5. In a wrench, a handle portion having a fixed jaw carried thereby, a longitudinally movable jaw co-operating therewith, said

last jaw being mounted for rotation and provided with a series of gripping teeth, and non-rotatable means co-operating with said element for limiting the effective penetration of said teeth into the article being gripped, substantially as described.

FRANK MOORE.
